C. SCHILLER.
PROTECTIVE APPARATUS FOR REPAIRERS OF BAKERS' OVENS.
APPLICATION FILED MAY 14, 1915.

1,152,554.

Patented Sept. 7, 1915.

UNITED STATES PATENT OFFICE.

CARL SCHILLER, OF NEW YORK, N. Y.

PROTECTIVE APPARATUS FOR REPAIRERS OF BAKERS' OVENS.

1,152,554.

Specification of Letters Patent.

Patented Sept. 7, 1915.

Application filed May 14, 1915. Serial No. 27,996.

To all whom it may concern:

Be it known that I, CARL SCHILLER, a citizen of Germany, and a resident of New York, in the county of Bronx and State of New York, have invented certain new and useful Improvements in Protective Apparatus for Repairers of Bakers' Ovens, of which the following is a specification.

In repairing the baking chambers of bakers' ovens, it has heretofore been found necessary to put the oven out of commission for a long period of time, sufficient for permitting the oven to cool down to such a temperature as would permit the operator to crawl into the chamber. By my invention this undesirable loss of time may be obviated, the operator being enabled to enter the chamber without inconvenience, while the latter retains substantially its high temperature.

In the accompanying drawing: Figure 1 is a plan of an apparatus embodying my invention, with the covering removed; Fig. 2 a similar view with the covering and roof removed; Fig. 3 a vertical longitudinal section of the apparatus; Fig. 4 an enlarged cross section on line 4—4 Fig. 3; Fig. 5 a similar cross section on line 5—5 Fig. 3 and Fig. 6 a detail.

A rectangular frame 1, formed of angle iron and reinforced by a number of cross bars 2, is adapted for the accommodation of a base plate 3, having a protuberance or head rest 4, near its forward end. To one of the longitudinal bars of frame 1, there are hinged at 5 a number of metal straps 6, the free ends of which are adapted to be removably secured to the opposite bar by winged nuts 7 (Fig. 6). Over straps 6 is spread a canvas- or similar covering 8, which is adapted to be secured to the straps by fasteners 9, the straps in conjunction with the covering constituting an openable roof. This roof extends however, only over the rear portion of the frame to here form a chamber, the front portion of the frame being furnished with a fixed bow 10, which is secured to the frame at a distance back of its forward end. From bow 10 extend forwardly a pair of grooved rails 11, adapted for the reception of a slidable window 12, the rails being secured at their forward ends, to bow 10 by removable braces 13. The forward extension of the roof, constructed as described, is furnished with separate canvas coverings 14 which extend from rails 11,

over braces 13, to the forward portions of frame 1, the whole constituting a hood.

To the rear of frame 1, there is hinged at 15 a foldable leg 16 which is of a length to reach the floor of the bakery while the frame rests upon the sole of the oven chamber. To an upper cross bar 17 of leg 16 is affixed a nozzle 18 adapted to be coupled by flexible pipe 19 to a fan or other generator of cooling air. Nozzle 18 extends a distance above the leg, the correlation of the parts being such, that when the leg is turned into a horizontal position, the nozzle will project a distance into the chamber beneath its roof.

In use, the apparatus is introduced with its forward end through the oven door, so as to be supported by the oven sole, while leg 16 is swung down (Fig. 3) to rest upon the floor of the bakery and hold nozzle 18 off the ingress end of the chamber. The operator crawls upon plate 3 until his chin rests upon protuberance 4, the attendant turns down the roof, closes it by the catches 7, and then pushes the entire device into the oven, during which manipulation, leg 16 will assume a horizontal position, while nozzle 18 will be projected into the back of the chamber. The nozzle being coupled to the cooled air generator, will cause a jet of such air to be passed over the body of the operator, which will protect him from the excessive heat of the oven. When repairs are to be made along the bottom of the chamber, the operator reaches beyond the end of frame 1, during which operation, the front canvas coverings 14 as well as braces 13 may be removed so that the operator has the free use of his arms.

When the repairs are to be made along the roof, braces 13 as well as coverings 14, are reinstated, and the operator turns upon his back when he can freely inspect the parts requiring his attention through window 12, which will protect his face from descending dust and loose particles.

I claim:

1. An apparatus of the character described comprising a frame adapted to be projected into a baking chamber, a base plate fitted within the frame, a roof extending over the frame to form a chamber, and means for injecting an air blast into said chamber.

2. An apparatus of the character described, comprising a base, a roof spanning the base, a leg hinged to the base, and a

nozzle carried by the leg and adapted to be projected beneath the roof.

3. An apparatus of the character described, comprising a frame, a plurality of straps hinged at one of their ends to the frame, means for removably securing the other ends of the straps to the frame, a covering carried by the straps, and means for injecting an air blast underneath the roof.

10 4. An apparatus of the character described, comprising a frame, a plate fitted

therein, an openable roof carried by the frame, a leg hinged to one end of the frame, and a nozzle carried by the leg.

5. An apparatus of the character de- 15 scribed, comprising a frame, an openable roof carried by the back of the frame, a leg hinged to the rear end of the frame, a nozzle secured to the leg, and a windowed hood carried by the front of the frame.

CARL SCHILLER.
